David S. Pearson
Sitters Patent

The vehicle referred to in these Sitters Patent and making fast of the
same maintaining a straight line in the road of the road David Pearson
himself of this maintaining same applied on Board Ships &c

This maintaining a place taken in the road of the tiller, as when up
when the tiller is a lee. The two ends of the tiller or wheel rope
are run through two blocks at the head of the tiller, and made
fast to two iron slides fastened to the tiller. Then are two maintain-
ing ropes fastened to the after end of the slides, then the after ends
of said ropes are run through the blocks fastened to the tiller
about 14 inches from the middle hand, then they are made fast
to two staples in the stock of the rudder about 8 feet from the
tiller, and when the tiller is run to keep the ropes are to be made
fast, then by moving the tiller a lee, the weather maintaining rope
haul, the weather slide will work down of the
tiller when the tiller runs a midship, by means of a staple on the of-
fer end of the slides. The weather slide will work down of the
tiller be moved from midship, but the lee one will not work
up so that the angle of the ropes of the tiller that makes the
stock rope is maintained by the same angle, by the application
of the iron slides, the maintaining ropes and pair blocks in a
manner above mentioned, which is a complete remedy for the 110
stock rope.
